UNITED STATES PATENT OFFICE

HUGO BRÜNINGHAUS, OF BARMEN-WICHLINGHAUSEN, GERMANY

METHOD OF AND APPARATUS FOR TYING PACKETS

Application filed September 21, 1929, Serial No. 394,371, and in Germany September 25, 1928.

The invention relates to a method and an apparatus for tying packets and the like by means of wire or metal strips. The application of wire in tying chests or cases offers no difficulties. In tying pasteboard packets or paper envelopes, however, the danger exists therein that the edges of the packet or envelope may be squeezed by the wire or metal strip, whereby also the content of the packet or envelope may be injured.

Furthermore, soft band iron and soft wire have the property of notably expanding upon traction being exerted thereon. The heavier the packet, the looser becomes the tied wire or strip during transport, when the packet is lifted or carried on the wire or strip.

Now in order to satisfactorily and securely tie pasteboard packets and the like by means of wire or metal strips, thin steel angle pieces or bars are placed on the edges of the packet according to the invention which angle pieces or bars take up the pressure exerted by the wire or metal strip merely during the tying operation and are withdrawn after this operation has been terminated.

The protection afforded to the packet during the tying operation by the steel angle pieces or bars enables the use of wire or metal strips of much greater thickness and of a hardness so as not to expand. In spite of this great hardness, with the present method the wire or strip can be placed onto the edges of the packet more tightly and at more correct angles.

The steel angle pieces or bars further may be shaped and applied so as to give way about as much as it corresponds to their thickness, so that after their removal the packet is so tightly tied as if tied without application of the angle pieces or bars.

In order that the invention can be more easily understood, an embodiment of a machine adapted to carry out the present method is diagrammatically illustrated in the accompanying drawing in which

Figure 1 is a side view of the machine,

Figure 2 is a front view thereof,

Figure 3 is a front view showing a modified form of the machine permitting adjustment for different packet sizes, and

Figure 4 is a lateral view of Figure 3.

Referring to these drawings, 1 denotes the supports interconnected by cross bars 2 and 3, so as to form a stationary frame and having mounted thereon angle irons 4 and 5 which form rails for a frame 6 adapted to run thereon. The lower bars 5 on their rear ends carry stops 7 for the frame 6. On their front ends the rails 5 converge into flat guides 8 that form a support for the packet 9.

The movable frame 6 possesses rollers 10 interconnected by longitudinal bars 11, cross-bars 12, and vertical supports 13, so that a box-shaped carriage is formed which can be shifted along the rails 4 and 5. This shifting motion of frame 6 is exerted by means of a hand lever 14 fulcrumed on a pin 15 of an upper longitudinal bar 16 of the stationary frame of the machine. Lever 14 has a handle 17 and is hingedly connected on its other end to a further cross bar 19 of frame 6. On another lower cross bar 20 of frame 6 is mounted a hook 21 having attached to it a cord 22 running on a pulley 23 mounted on a cross bar 24 fixed on the rails 5. Cord 22 carries a weight 25 and tends to shift frame 6 to its foremost position.

In this foremost position of frame 6 guide bars 26 which extend in the prolongation of the longitudinal bars 11 abut on the edges of the packet 9 and in this position can be applied to the latter by the tying means denoted by 27.

As soon as the tying means 27 have been applied, frame 6 is withdrawn by means of hand lever 14. When this takes place, stops 28 and 29 rigidly connected to the supports 1 come to abut both on the tying means and on the rear surface of the packet. The latter and the tying means 27 are thereby prevented from taking part in the rearward motion of frame 6. The tied packet 9 thus remains on the bars 8 from which it can be easily withdrawn.

The stops 28 and 29 may be designed so as to be adjustable for different packet sizes, this arrangement, however, being not shown for the sake of clearness.

Furthermore, the machine may be designed in such a manner that the steel angle pieces

or bars are stationary and the packet is moved out of the machine by frame 6.

In order to adjust the bars 26 for different packet sizes, a movable frame may be used as illustrated in Figures 3 and 4. The rollers 10 of this frame are mounted on rings 30 or any other suitable member which rings carry adjustable levers 31 pivoted on pins 32 and adapted to be fixed in the adjusted inclined position by means of clamp screws 33 guided in slots 34 of the rings 30, all as clearly shown in Figures 3 and 4. The levers 31 further carry longitudinally shiftable sleeves 35 adapted to be fixed on them by clamp screws 36 and carrying in their turn sleeves 37 which extend normally thereto and commonly carry the respective bars 26. By means of the clamp screws 38 the bars can always be set so as to correctly abut on the edges of the packet.

The movable frame as illustrated in Figures 3 and 4 may be used likewise in connection with the stationary frame fitted with the rails 4, 5 as illustrated in Figures 1 and 2. Of course, in other respects the construction of the movable frame 6 may be any other suitable one.

I claim:

1. An apparatus of the kind described, comprising a frame, a carriage adapted to run thereon and to receive a packet to be tied, angle pieces mounted on said carriage and adapted to abut on parallel edges to be embraced by a tying means, of the packet upon said carriage running in one direction, and means for shifting the packet out of said angle pieces and carriage upon the latter running in opposite direction.

2. An apparatus of the kind described, comprising a frame, a carriage adapted to run thereon and to receive a packet to be tied, angle pieces mounted on said carriage and adapted to abut on parallel edges to be embraced by a tying means, of the packet upon said carriage running in one direction, and means for shifting the packet out of said angle pieces and carriage upon the latter running in opposite direction, said angle pieces being adapted to be adjusted for different packet sizes.

3. An apparatus of the kind described, comprising a frame, a carriage adapted to run thereon and to receive a packet to be tied, angle pieces mounted on said carriage and adapted to abut on parallel edges to be embraced by a tying means, of the packet upon said carriage running in one direction, stops mounted on said frame adapted to engage a front surface of said packet so as to shift it out of said angle pieces and carriage upon the latter running in opposite direction.

4. An apparatus of the kind described, comprising a frame, a carriage adapted to run thereon and to receive a packet to be tied, angle pieces mounted on said carriage and

adapted to abut on parallel edges to be embraced by a tying means, of the packet upon said carriage running in one direction, stops mounted on said frame adapted to engage both a front surface of said packet and a tying means applied thereon so as to shift the packet out of said angle pieces and carriage upon the latter running in the opposite direction.

5. An apparatus of the kind described, comprising a packet support; means forming a guideway to the support; a carriage movable in the guideway to and from the support and adapted to receive therefrom a packet to be tied; and means on the carriage to protect the edges of the packet from ties when in the carriage and to guide closely said ties about said packet.

6. An apparatus of the kind described, comprising a packet support; means forming a guideway to the support; a carriage movable in the guideway to and from the support and adapted to receive therefrom a packet to be tied; means on the carriage to protect the edges of the packet from ties when in the carriage and to guide closely said ties about said packet; and means for automatically moving the carriage to the packet support.

7. An apparatus of the kind described; comprising a packet support; means forming a guideway to the support; a carriage movable in the guideway to and from the support and adapted to receive therefrom a packet to be tied; means on the carriage to protect the edges of the packet from ties when in the carriage and to guide closely said ties about said packet; means for automatically moving the carriage to the packet support; and means for freeing the tied packet from the carriage when the latter is moved away from the support.

8. An apparatus of the kind described; comprising a packet support; means forming a guideway to the support; a carriage movable in the guideway to and from the support and adapted to receive therefrom a packet to be tied; means on the carriage to protect the edges of the packet from ties when in the carriage and to guide closely said ties about said packet; means for automatically moving the carriage to the packet support; means for freeing the tied packet from the carriage when the latter is moved away from the support; and manually operated means for moving the carriage away from the support.

9. An apparatus of the kind described; comprising a packet support; means forming a guideway to the support; a carriage movable in the guideway to and from the support and adapted to receive therefrom a packet to be tied; means on the carriage to protect the edges of the packet from ties when in the carriage and to guide closely said ties about said packet; means for automatically moving

the carriage to the packet support; means for freeing the tied packet from the carriage when the latter is moved away from the support; means manually operated for moving

5 the carriage away from the support; and means for adjusting the protecting means correspondingly to the size of the packet to be tied.

10. A method of tying packets, packages and the like by means of wire or metal strips which comprises placing thin metal angle pieces on the edges and corners of the packet to be tied; applying the wire or metal strip around the packet on the angle pieces and

15 tying the ends thereof; and removing the angle pieces from the tied packet.

11. A method of tying packets, packages and the like by means of wire or metal strips which comprises placing protecting pieces

20 around the corners and edges of the packet to be tied; applying and tying the wire or strips around the packet on the protecting pieces; and removing the protecting pieces from the tied packet.

25 In testimony whereof I have affixed my signature.

HUGO BRÜNINGHAUS.
